A fragmentary side elevational view of a vegetable packaging machine showing a rigid base member 10 supporting a prime mover or motor 11 having a laterally extending shaft 12 with a bevel gear 13 affixed thereon. The bevel gear 13 engages a similar but larger bevel gear 14 mounted on a vertical shaft 15, the latter affixed to the under surface of a table 16 in parallel alignment with the base 10.

UNITED STATES PATENT OFFICE

2,510,541

COMMODITY SACKING MACHINE WITH ROTATABLE TABLE HAVING DISCHARGING FUNNELS COMBINED WITH SACK SUPPORTING CHUTES

Hiram M. Beeson, Dallas, Tex.

Application July 2, 1946, Serial No. 681,041

3 Claims. (CL 226—2)

1

This invention relates to machines adapted to facilitate packaging of fresh produce and more particularly to devices of this nature used in packing green vegetables into usually limp containers such as paper or cellophane bags.

The preferable embodiment of the invention consists of a circular table having an angular peripheral retaining flange with spaced apertures therethrough for receiving produce for packaging, the table being rotated by a vertical axle attached to a table supporting frame, the axle being actuated by means of a prime mover and suitable reduction gears. Immediately below the table a conveyor moves continually while the machine is in operation to carry discharged packages to a point for further handling.

The principal object of the invention is to provide an improved machine to aid in packaging fresh vegetables.

Another object of the invention is to provide a machine of the character described adapted for rapid packaging of fresh vegetables by a number of workers stationed at intervals around a rotating table.

Still another object of the invention is to provide a machine of the character described, being of simple construction of available materials with the additional feature of easy operation.

A further object of the invention is to provide a machine of the character described adapted for economical manufacture and maintenance.

With the foregoing objects as paramount, this invention has further reference to certain features of accomplishment which will become apparent as the description proceeds, taken in connection with the accompanying drawings, wherein:

Figure 1 is a fragmentary top plan view of a vegetable packaging machine constructed according to the invention.

Figure 2 is a side elevational view of the invention shown partially in section to illustrate the table top construction.

Figure 3 is a fragmentary side elevational view in greater detail to illustrate pertinent construction details, and

Figure 4 is a fragmentary perspective view of the parts shown in Figure 3 to illustrate the manner of releasing filled bags onto the conveyor.

Continuing with a more detailed description of the drawings, and referring to Figures 1 and 2, a rigid base member 10 supports a prime mover or motor 11 having a laterally extending shaft 12 with a bevel gear 13 affixed thereon. The bevel gear 13 engages a similar but larger bevel gear 14 mounted on a vertical shaft 15, the latter affixed to the under surface of a table 16 in parallel alignment with the base 10.

Angularly disposed frame members 17, affixed to the base 10, support a circumferentially placed dual trackway or rail 18, the purpose of which will be presently described. A peripheral angular flange of the table 16 is perforated at spaced predetermined intervals, each perforation having a trunco-conical annulus or funnel 19 independent therefrom for the dual purpose of engaging the open end of a bag 20 and to provide an opening for receiving produce to be packed into the bag 20 so retained in an erect position. A flanged dependent plate or chute 21 is affixed at right angle to the peripheral flange of the table 16, centrally placed with reference to the annulus 19 for the purpose of affording a rest for one side of the bag 20 while being packed. A flat plate 20 or flap 22 is hinged at the lower end of the plate 21 thus forming a point of rest for the bag 20 while being packed.

The reason for hinged connection will be more fully explained hereinafter. Angularly disposed supporting bars 23 serve to maintain the plate 21 rigidly in its position with relation to the table 16.

In operation as a vegetable packing table the produce to be packed is placed upon the flat portion of the table 16 in a manner to leave the apertures accessible to workers stationed at intervals around the table 16. The motor 11 is energized thereby starting the rotation of the table 16 in a counterclockwise direction. A continuous conveyor belt 24 moves in unison with the rotation of the table 16 to carry packed bags to a point of further handling. Rigid side rails 25 serve to retain the bag 20 upon the conveyor belt 24 to the point of further handling or disposal.

In the process of packing, a bag 20 is placed upon the plate 22, its open end engaging the outer surface of the annulus 19, the plate 22 being slidably supported upon the dual trackway 18. A worker manually places through the aperture and annulus 19 a sufficient quantity of produce to substantially fill the bag 20. The filled bag, being continually moving by virtue of the rotation of the table 16, is carried to a point 26 of the trackway 18 where the normal continuance of the outer portion of the trackway is abruptly terminated, as shown in detail in Figure 4. At this point 26 the inner portion of the trackway 18 is offset inwardly and downwardly, the resultant loss of support of the plate 22 allowing said plate 22 to drop, thus releasing the

55

upon the plate 22, its open end engaging the outer surface of the annulus 19, the plate 22 being slidably supported upon the dual trackway 18. A worker manually places through the aperture and annulus 19 a sufficient quantity of produce to substantially fill the bag 20. The filled bag, being continually moving by virtue of the rotation of the table 16, is carried to a point 26 of the trackway 18 where the normal continuance of the outer portion of the trackway is abruptly terminated, as shown in detail in Figure 4. At this point 26 the inner portion of the trackway 18 is offset inwardly and downwardly, the resultant loss of support of the plate 22 allowing said plate 22 to drop, thus releasing the

packed bag 20 to fall upon the conveyor belt 24 to be carried thereby to a point of disposal.

From the point 26 the inner trackway 18 curves upwardly and outwardly until it assumes its normally curvilinear position at point 27, this gradual resumption of its position serving to raise the plate 22 to its normal bag-supporting position as the table 16 continues to rotate.

Manifestly, the construction as shown and described is capable of some modification and such modification as may be construed to fall within the scope and meaning of the appended claims is also considered to be within the spirit and intent of the invention.

What is claimed is:

1. A commodity sacking machine comprising a circular rotatable table having an inclined, circumferential flange provided with equidistantly spaced openings, a funnel embracing the wall of each of said openings and depending from the underside of said flange and through which commodity is deposited into a sack from said table, an inclined chute disposed under each of said funnels and also depending from said flange for supporting a sack in filling position, a flap hinged to the lower edge of said chute, an annular rail subjacent to said flange adapted to hold said flap in elevated position, said rail having therein an abrupt drop and a gradual rise to respectively release and resume the support of said flap to discharge a filled sack from said chute and means for rotating said table.

2. A commodity sacking machine comprising a rotatable table having an inclined annular flange provided with annularly spaced openings, an inclined chute attached to and suspended below said flange adjacent each opening therein, a funnel embracing the wall of each opening below said flange adapted to retain a sack and through

which commodity from said table is thrust into said sack, a flap hinged to the bottom of each of said chutes, an annular and stationary rail disposed below said flange to support the flaps of said chutes and whose continuity is broken at one point by an abrupt drop and a gradual rise to respectively drop said flaps to release a filled sack and to assume support of unfilled sacks and means for rotating said table.

3. A machine for sacking leafy vegetables including a rotatable table adapted to support the vegetables to be sacked, an annular, inclined retaining flange surrounding the perimeter of said table and having annularly spaced openings adjacent its periphery through which vegetables are manually thrust, means under said flange and embracing the wall of each of said openings on which a sack is mounted to receive said vegetables, an inclined chute adjacent said sack mounting means, a hingedly displaceable flap on said chute for supporting said sack, an annular and stationary rail below said table for maintaining said flap in sack supporting position and whose continuity is interrupted at one point by an abrupt drop to release said flap to discharge a filled sack and an adjacent gradual rise to return said flap to sack supporting position and means for rotating said table.
